UNITED STATES PATENT OFFICE.

JOHN E. SCHONACKER, OF DAYTON, ASSIGNOR TO JAMES W. CUMMINGS,
OF SPRINGFIELD, OHIO.

ARM-REST FOR BOOKS.

SPECIFICATION forming part of Letters Patent No. 358,698, dated March 1, 1887.

Application filed July 22, 1886. Serial No. 208,698. (No model.)

To all whom it may concern:

Be it known that I, JOHN E. SCHONACKER, of the city of Dayton, county of Montgomery, and State of Ohio, have invented certain new 5 and useful Improvements in Arm-Rests for Books, of which the following is a specification.

This invention relates to arm-rests to be used with books, the object of the invention being to provide a cheap, simple, and durable device to support the arm of a person when writing in books of considerable thickness—such as legal books, journals, ledgers, &c.—and to so construct the arm-rest and its component 15 parts that it may be quickly adjusted to different heights, inclined to different angles in the direction of its width, and its arm-rest portion be extended out more or less to give more bearing-surface for the arm of the writer.

With these objects in view my invention consists in the construction, combination, and arrangement of the several parts of the arm-rest, substantially as hereinafter described and claimed.

Figure 1, Sheet 1, represents in isometrical perspective an arm-rest constructed in accordance with my invention as applied to a book; Fig. 2, a side elevation of the arm-rest; Fig. 3, a front end view of the same; Fig. 4, an enlarged detail of a portion of one of the supporting-legs, showing the construction of one of the clamping-washers; Fig. 5, Sheet 2, illustrates in isometrical perspective a modified form of arm-rest as applied to a book; Fig. 6, 35 a side elevation of the arm-rest illustrated in Fig. 5; Fig. 7, an end view of the same, and Fig. 8 details of the clamping-screw.

In the drawings, A represents the arm-rest proper, which consists of the end a with the projecting blade b, said parts being preferably 40 constructed of wood, and similar to the ordinary arm-rests now in use.

Pivoted to the forward end of the portion a of the arm-rest is a series of legs, c d d, said 45 legs being pivoted to the portion a near its sides.

As shown in Figs. 1 and 2, there will preferably be two legs, d d, pivoted to one side of the portion a of the arm-rest, these legs 50 being pivoted at their upper end to the depending lug or eye e, which in turn is secured

to the portion a, preferably by screwing its shank e' into the portion a, as shown in Fig. 2.

The leg c is pivoted at its upper end between ears of the depending lug f, secured to the other side of the portion a in a like manner as lug e. This leg c extends downward between the two legs d d, said legs being crossed, as clearly shown in Fig. 3.

Each leg has a central slot, f', extending in 60 the direction of its length, as shown in the drawings. The legs are secured together and held in place by means of a thumb-screw, g, the shank of which extends through the slots f' in the legs, washers h being provided to 65 bear against the legs d d when pressing said legs tightly against the leg c. These washers each have a central projection, i, upon their inner faces to fit the slots f' in the legs d d, said projection preventing the possibility of 70 the washers turning.

The legs c d d, as well as the slots f', formed therein, may be of greater or less length, as may be desired.

To provide for the extension of arm-rest portion a, I have provided the same with an extension-piece, k, said piece being movably secured to the portion a at its upper side, preferably by means of guides l l l' l', two of which guides, l l, are secured to the upper face of the 80 piece k and overlap the side edges of the portion a of the arm-rest, and the other two of which guides, l' l', are secured to the side edges of the portion a and overlap the upper face of the piece k. These guides will preferably be 85 of metal and of angle construction. By the use of such guides I effectually secure the extension-piece k to the portion a of the arm-rest and permit it to be easily moved outward to lengthen the bearing for the arm of the 90 writer.

Secured to the forward end of the piece k is a depending piece, m, which extends transversely across the end of said piece k and downward in close proximity to the blade b of the 95 arm-rest, a piece of felt or other flexible material, n, being interposed between the piece m and blade b.

The extension-piece k will preferably be made of thin wood; but it is obvious that it 100 could be made of sheet metal, in which case the piece m and guides l l would be formed a

part with said piece by turning over portions of the metal. Therefore I do not desire to limit myself to the exact construction illustrated in Fig. 1, Sheet 1.

5 The construction of the arm-rest as a whole, as above described, is more practical, I believe, than the one illustrated on Sheet 2 of the drawings, and is therefore preferable.

10 The difference between the arm-rest above described and the one illustrated on Sheet 2 of drawings consists simply in providing only two legs to support the arm-rest instead of three, and pivoting the said legs at their upper ends to the extension-piece *k* instead of 15 securing them to the portion *a* of the arm-rest proper, the said legs being secured together by a thumb-screw, and being of a similar construction to those illustrated in Fig. 1, Sheet 1.

10 The two arm-rests illustrated in the two sheets of drawings being mechanically equivalent insofar as principle and operation are concerned, I desire to make my claim of sufficient scope to cover both constructions.

20 By reference to the drawings the operation of the arm-rest will be readily understood.

25 By the construction described I am not only enabled to increase or decrease the height of the arm-rest with reference to the book, but may also incline the arm-rest more or less to 30 bring it upon the same plane of the book should the book be inclined or tipped in any manner. This may be easily and quickly done, it being simply necessary to loosen the thumb-screw, slide the legs up or down relatively to each 35 other, and tighten the thumb-screw.

The blade *b* is extended into the book between the leaves in the usual manner, the ends of the legs resting upon the table or desk.

The portion *a* will preferably have a slot, *o*, in its upper face, near the center, to allow the 40 finger to be inserted when sliding the extension-piece *k* outward.

I claim—

1. An arm-rest for books, composed of the supporting-board *a b*, the legs pivoted to the 45 portion *a* and adjustably secured together, and the extension-piece *k*, movably secured to the portion *a*, all substantially as described.

2. The combination, in an arm-rest, of the supporting-board *a b* and the extension-piece 50 *k*, movably secured to the portion *a* by means of the guides *l l' l' l*, substantially as described, and for the purpose set forth.

3. An arm-rest composed of the main supporting-board *a b*, the two legs *d d*, pivoted to the portion *a* near its forward end, the one leg *c*, pivoted thereto and extended between the two legs *d d*, as described, said legs having the central elongated slots, *f f'*, therein, the screw *g*, securing said legs adjustably together, and the extension-piece *k*, adjustably secured to the portion *a* of the supporting-board by means of suitable guides, said piece *k* having the depending piece *m* at its end, all constructed and arranged substantially as and for the purpose 65 described.

In witness whereof I have hereunto set my hand and seal, at Springfield, Ohio, this 16th day of July, A. D. 1886.

JOHN E. SCHONACKER. [L. S.]

In presence of—

P. J. CLEVENGER,
N. E. C. WHITNEY.
